UNITED STATES PATENT OFFICE.

EDWARD C. NEWCOMB, OF SCITUATE, MASSACHUSETTS, ASSIGNOR TO STANDARD ENGINEERING COMPANY, OF ST. LOUIS, MISSOURI, A CORPORATION.

WATER-PUMP.

1,336,258.

Specification of Letters Patent. Patented Apr. 6, 1920.

Application filed January 28, 1919. Serial No. 273,637.

To all whom it may concern:

Be it known that I, EDWARD C. NEWCOMB, a citizen of the United States, residing in the town of Scituate, county of Plymouth, 5 and State of Massachusetts, have invented new and useful Improvements in Water-Pumps, of which the following is a specification.

This invention relates to pumps, and has 10 for its general object to provide a novel construction of water pump the barrels of which are relatively long as compared with their diameter and in which the use of stuffing boxes for the pump pistons is dispensed with.

The invention has for its special objects 15 to mount the pump barrels in such manner that they can be readily placed in true alinement with each other and will have no tendency to be moved out of alinement when once secured in position; to provide 20 novel means for collecting and draining off water which may seep or be forced, in the operation of the pump, between the wall 25 of the pump and the piston; and to provide certain novel details of construction and combinations and arrangements of parts, whereby a water pump of great utility and efficiency is provided.

30 My improved pump is illustrated in the accompanying drawing in which the figure is a view partly in side elevation and partly in section of a pump constructed according to my invention.

35 Referring to the drawing the numeral 1 indicates the pump frame, which is in the form of a hollow open-sided casting having heads 2, 3, respectively, at opposite ends, and a base 4. The pump as a whole is 40 mounted in a casing 5 adapted to contain oil, and the base 4 of the pump frame is bolted to the bottom 6 of this casing, as indicated at 7. Each of the heads 2, 3, is provided with a cylindrical aperture 8, each 45 aperture being surrounded on its outer side by a plurality of screw-threaded openings 9. The numerals 10, 11 indicate, respectively, two pump barrels, which are secured in endwise relation on the heads of the

pump frame in such manner that their bores 50 will be in exact alinement. To this end each pump barrel is provided with an integral annular flange 14 located at a suitable distance from the inner end of the barrel, so that when said inner end is inserted in the 55 aperture 8 the inner face of the flange 12 will abut, and lie flush against, the outer faces of the respective heads 2, 3. Each of the apertures 8 is of slightly greater diameter than the diameter of the pump barrel 60 inserted therein. The purpose of this construction is to permit of the movement of either pump barrel to adjust its bore into exact alinement with the other pump barrel. Each flange 12 is provided with a series of 65 apertures 13 designed to aline with the screw-threaded openings 9, and through which apertures screw-threaded bolts are passed and screwed into the openings 9 for bolting each barrel to its respective head 2, 70 3. The apertures 13 are of slightly greater diameter than the diameter of the bolts so as to permit of the slight movement of the barrel and flange in adjusting it in its alinement position with the other barrel. After 75 being positioned the bolts 14 are screwed home, and the heads of the bolts 14 engaging the outer face of the flange 12 will bind the latter, in each case, in firm engagement with the corresponding head of the pump 80 frame, as will be understood. If desired suitable keys or wedges may be inserted between the shank of the bolt 14 and the bore of the opening 13, and between the pump 85 barrel and the wall of the aperture 8, in each instance, to more securely hold the pump barrel in its adjusted position. But as provisions of such means are obvious and within the skill of an ordinary mechanic, they are not illustrated, particularly as they 90 would ordinarily not be required. At their outer ends each of the barrels 10 and 11 is provided with a valve chamber 14, in which is located an inlet valve 16, governing the inlet from a water supply pipe 17, and an 95 outlet valve 18, controlling an outlet 19. The water supply pipe 17 extends through the bottom 6 of the casing 5, and where it

passes through, a stuffing-box 20 is secured to the under side of said bottom, the purpose of said stuffing-box being to prevent the escape of oil from the casing 5. The pipe 17 is not in any manner secured, or fixed to, the bottom 6, so that in the event of relative movement between the pump barrel and the casing the pipe could move in its bearing in said bottom. The purpose of this arrangement is to prevent any tendency to force either of the pump barrels out of its true alinement with the other barrel, which might occur if a rigid connection were made between the pipe 17 and the bottom of the casing 5.

To accomplish the object of draining from the pump barrels any water which may seep or be formed between the piston and the bore of the pump barrel, I provide on the interior of each barrel an annular groove 21, communicating with the bore of the barrel, and secure in a screw-threaded opening, communicating with said groove, a pipe 22, which also extends through the bottom 6 and passes through a stuffing-box 23, the pipe 22 being movable in said stuffing-box for the same purpose as described in connection with the pipe 17. The pipe 22 may communicate with the suction side of the pump, or the water escaping through the same may be permitted to drop on the ground.

While the annular groove 21 may be located at any preferred point in the length of each pump barrel, I have considered it desirable to locate the same in the inner end portion 25 of the pump barrel which projects into the aperture 8. Each of the heads 2, 3, will, therefore, be provided with an opening extending through the base of the frame 1 to permit the pipe 22 to be passed up through said opening and secured in the pump barrel.

The numeral 26 indicates the double-acting pump piston, which is in the form of a cylindrical rod, its end portions extending into and having working engagement with, the bores of the respective pump barrels. Secured centrally of the piston 26 in the open space of the frame 1 is a cross-head 27, which is connected to a bifurcated pitman rod 28 by means of a cross-pin 29, the pitman rod spanning the frame 1, as will be understood. The inner end 30 of said pitman rod is connected to a crank pin 31 upon an eccentric 32 secured on a drive shaft 33.

While the invention is, of course, not limited to size, proportions or exact details of construction, it may be stated that each of the pump barrels is approximately ten inches long and one-half inch in diameter, and the piston 26 has a stroke of about one and a quarter inches.

This size of pump is intended for use in steam automobiles to pump water to the boiler; but it is obvious that the same principle could be employed in pumps of larger size and for other purposes.

It will be noted that each of the pump barrels is wholly supported by being connected at its inner end to the respective heads 2, 3, and said barrels being of considerable length as compared with their diameter, and the piston rod having consequently such a long bearing within each of the pump barrels, there is very little tendency of the two barrels working out of alinement, as it will be observed that they are in effect held in alinement by the piston rod itself. The pump as a whole being supported by means of the base 4 on the bottom of the casing 6, and there being no other fixed connection between the pump barrels and said casing, it is obvious that any movement of the casing will effect the pump as a whole, and there will be no force exerted on one barrel which will not equally affect the other barrel.

By providing the annular groove 21 with the escape pipe 22 I prevent any water escaping into the casing 5, which as stated contains oil, and thus dispense with the necessity of employing stuffing-boxes for the piston.

While I have shown and described the pistons for the pumps as consisting of a single rod, the opposite ends of which work in the respective pump barrels, it is obvious that I can employ separate rods and connect them at the center to the cross-head, in a well known way.

I claim:

1. A duplex pump comprising a frame, alining pump barrels adjustably secured at their inner ends to said frame and being thereby wholly supported, and a unitary piston common to said barrels.

2. A duplex pump comprising a hollow frame, alining pump barrels adjustably secured at their inner ends to opposite ends of said frame and being thereby wholly supported, a unitary piston common to said barrels, and a driving connection for said piston secured thereto intermediate the ends of the frame.

3. A duplex pump comprising a frame, alining pump barrels adjustably secured at their inner ends to opposite ends of said frame and being thereby wholly supported and a unitary piston common to said barrels.

4. A duplex pump comprising a frame provided at opposite ends with apertured heads, alining pump barrels having inner end portions loosely seated in the respective apertures and provided, respectively, with annular flanges seated against said heads, bolts securing said flanges to said heads, and

loosely received in apertures in said flanges, and a unitary piston rod having opposite end portions working in said pump barrel.

5. A duplex pump comprising a frame, elongated alining pump barrels secured at their inner ends to said frame and being thereby wholly supported, a piston common to said barrels, a casing inclosing said pump and adapted to contain oil for the lubrica-

tion thereof and supply pipes communicating with said barrels and passing loosely through a wall of said casing to permit relative movement between the casing and pump barrels without thereby causing said pipes to exert pressure upon said barrels.

In testimony whereof, I have hereunto set my hand.

EDWARD C. NEWCOMB.
